UNITED STATES PATENT OFFICE.

WILLIAM E. ULRICH, OF DETROIT, MICHIGAN.

METALLIC WINDOW-SASH.

991,042.

Specification of Letters Patent. Patented May 2, 1911.

Application filed August 3, 1910. Serial No. 575,296.

To all whom it may concern:

Be it known that I, WILLIAM E. ULRICH, citizen of the United States, residing at Detroit, county of Wayne, State of Michigan, have invented a certain new and useful Improvement in Metallic Window-Sash, and declare the following to be a full, clear, and exact description of the same, such as will enable others skilled in the art to which it pertains to make and use the same, reference being had to the accompanying drawings, which form a part of this specification.

My invention relates to an improvement in metallic window sashes, and particularly the means of interlocking the vertical and cross mullions with each other,—the object being to so construct the interlocking portion of these cross members that they may be engaged with each other and securely locked without distorting the regularity of the bars, the symmetrical appearance of the sash being thereby preserved.

A further object is to provide means whereby cross and vertical mullions of the same relative size may be interlocked, without either presenting a bulged appearance at the point of intersection,—the objection to sash as now manufactured employing mullions of the same cross-sectional area.

Other advantages and improvements will hereafter appear.

In the drawings accompanying this specification: Figure 1 is an elevation of the metallic sash. Fig. 2 is a perspective view of a fragmentary portion of a cross mullion notched to receive the engaging member. Fig. 3 is a similar view of the vertical mullion. Fig. 4 is a fragmentary perspective view of the cross and vertical mullions interlocked.

Referring now to the letters of reference placed upon the drawings:—A is the frame of the sash mortised to receive the ends of the cross and vertical mullions and to which they are riveted.

The mullion A' is punched as indicated at A² for the passage of the mullion B in turn notched at b, b, to receive the connecting members a, a', bridging the opening punched in the cross member A'.

a², a² are lugs formed by shearing the web A³ backward from the central opening A² a suitable distance as indicated at a³ in Figs. 2 and 4, sufficient metal being cut away from the ends of the lugs to admit of the passage of the web portion B' of the member B.

The cross member a' is bent slightly as indicated in dotted lines for the passage of the mullion B and when assembled the cross members a, a', are forced into the notches b, b, of the connecting mullion making them flush with the top and bottom of the intersecting member. The lugs a² are then bent back (as shown in Fig. 4) in line with the main body of the web portion whereby the mullions A' and B are securely locked together.

A great advantage is gained in the strength and appearance of the sash by the use of this invention as I am enabled to employ cross and vertical mullions of the same size,—the surfaces of the intersecting mullions being flush with each other when interlocked,—a much handsomer appearance being thereby obtained than is possible in constructions where it becomes necessary to form a hump at each intersection in order to provide a passage for the cross members, or in constructions requiring one set of mullions to be larger than the intersecting members.

Having thus described my invention, what I claim is:—

1. Two sets of cross jointed bars of equal size in cross section, one set of bars formed with bridged apertures and slit to form lugs adapted to be bent to receive and lock the cross members, and the cross members notched on both edges to receive the portions bridging the openings of the other set of members, whereby the edges of both sets of bars are flush when assembled and locked.

2. Two sets of cross jointed bars of equal size in cross-section, one set punched with openings for the passage of intersecting bars, a portion being left on either side to bridge said openings, lugs integral with the bars formed by slitting the metal backward a suitable distance from the openings, and the intersecting bars notched at both of their edges to receive the portions bridging the openings of the first named members, the lugs of said first named members bent to the plane of their body portion when the cross and intersecting bars are assembled and the portions bridging the openings lodged in the notches of the other member, whereby the said cross bars are interlocked.

3. In a window sash, the frame, two sets of cross jointed bars of equal size in cross-section secured to the frame, one set of bars formed with bridged apertures and slit to

form lugs adapted to be bent to receive and lock the cross members, and the cross members notched on both edges to receive the portions bridging the openings of the other set of members, whereby the edges of both sets of bars are flush when assembled and locked.

In testimony whereof, I sign this specification in the presence of two witnesses.

WILLIAM E. ULRICH.
